UNITED STATES PATENT OFFICE

HYMAN GERTLER, OF MONTREAL, QUEBEC, CANADA

INFANT'S CRIB

Application filed October 3, 1928. Serial No. 310,134.

This invention relates to improvements in infants' cribs of the type having vertically movable sides which may be secured in raised positions in which they form the regular sides of the crib to prevent the child from falling out of the crib and which may be moved into lowered positions in which the crib side is open so that the child may pass freely from the crib and the object of the invention is to provide an improved manner of detachably securing the sides in raised positions in which, while the side is securely supported, it may be readily and conveniently lowered.

The invention consists in the construction, and arrangement of parts, all as hereinafter more particularly described and illustrated in the accompanying drawings in which,

Figure 1 is a side elevation of the improved crib broken intermediately, the left hand end showing the side in the raised position and the right hand end showing the side in the lowered position.

Figure 2 is a fragmentary side elevation showing a portion of one of the corner posts of the crib and the manner of supporting the side in the raised position.

Figure 3 is a face view of a depending latch supported from the corner post and used for supporting the side in the raised position, a portion of the corner post being indicated in broken lines.

In the form illustrated the crib consists of a frame having corner posts 4 and vertically movable sides 5. Each corner post carries upper and lower lugs 6 and 7 in which are mounted vertical rods 8 which rods pass through orifices in the sides 5 and form guides for the sides. Loosely hung from each upper lug 6 is a depending latch 9 the lower extremity of which is inclined inwardly towards the corner post at 10.

Each latch 9 is substantially U-shaped in its upper end so as to form a member with a long and a short arm. The long arm is provided with a rectangular opening 9^a slightly deeper than the thickness of lug 6, while the short arm is bored with an opening 9^b appreciably deeper than the thickness of lug 6. Owing to the arrangement, al-

though the position of rest will be as shown in full lines in the drawings, it will be possible through the action of the ends 12 of the side 5 to move the latch to the dotted line position shown in Figure 2. After the member 5 is brought in line with the opening 11, the latch 9 will automatically fall back to its position of rest, thus engaging the end 12 and maintaining the side in its raised position.

Considering the side 5 to be in its lowered position, as indicated at the right in Figure 1, in order to secure it in the raised position it is merely necessary to move it upwardly on the guide rods 8 and as it reaches its upper position the projecting ends 12 at each end of the upper edges of the side engage the inclined portions 10 of the latches 9 and move them outwardly until the projecting ends 12 are opposite the orifices 11 when the latches 70 are free to move back to the full-line position of rest, thus engaging the free ends 12.

In order to lower the side, the lower ends of the latches 9 are simply pressed outwardly towards the corner posts, which releases the 75 projecting ends 12 from engagement within the orifices 11 and the side is free to be lowered.

It will thus be seen that the clips 9 detachably engage the projecting ends 12 of the 80 sides for supporting the sides in the raised positions.

From the foregoing it will be evident that the invention provides a very convenient and reliable manner of supporting the movable 85 sides of cribs of the type described and whereby the objects of the invention have been attained.

As many changes could be made in the above construction and many apparently 90 widely different embodiments of my invention, within the scope of the claims, constructed without departing from the spirit or scope thereof, it is intended that all matter contained in the accompanying specification and drawings shall be interpreted as illustrative 95 and not in a limiting sense.

What I claim as my invention is:

1. An infant's crib comprising a frame having corner posts, vertically movable sides for 100

the crib adapted to occupy a raised and a lowered position, upper and lower lugs rigidly carried by each corner post, vertical rods mounted in said lugs and forming guides upon which the sides slide, depending latches substantially of U-shape, each arm of the U-shaped latches being provided with rectangular openings loosely engaging the upper lugs, one of the arms of the U-shaped latches being longer than the other and provided with a hole, and projections on the sides adapted to be brought into detachable engagement with the latches through the holes.

2. The combination with an infant's crib, having a frame with corner posts, a vertically movable side and rods on which the side is mounted spaced from the posts, the said posts having lugs supporting the ends of the rods, of a latch member mounted on one of the lugs, said latch member being of U-shape with a shorter and longer arm, each arm being provided with a perforation through which the lug extends, the perforation of the shorter arm being appreciably deeper than the thickness of said lug whereby the latch may tilt on the lug.

3. An infant's crib comprising a frame, corner posts for said frame, upper and lower lugs mounted in said corner posts and carrying vertical guide rods, side members slideable on said guide rods and gravity actuated latches hung on said upper lugs, each latch comprising an arm having an opening therein through which said lug passes, said opening being slightly deeper than the thickness of said lug to allow said arm to tilt inwardly towards said corner post, said arm having a further opening therein intermediate its lower end and said first mentioned opening, said arm being bent inwardly towards the corner post at the lower end thereof, means integral with the latch for spacing said arm outwardly from said post and projections on said side members for making detachable connection with said latches through said second mentioned openings.

In witness whereof I have hereunto set my hand.

HYMAN GERTLER.
